CLAIM

The ornamental design of an all-in-one pocket-sized vital-sign monitoring apparatus, as shown and described.

DESCRIPTION

1. All-in-one pocket-sized vital-sign monitoring apparatus
- 1.1 : left
- 1.2 : Right
- 1.3 : Front
- 1.4 : Back
- 1.5 : Perspective
- 1.6 : Top
- 1.7 : Bottom
